PROCESS OF COLOR ANALYSIS AND COLOR
SYNTHESIS FOR THE PROJECTION OF
COLORED PICTURES IN PHOTOGRAPHY
AND CINEMATOGRAPHYItalo Ferriguto and Alessandro Meauro,
Rome, ItalyApplication September 19, 1938, Serial No. 230,718
In Italy August 22, 1938

1 Claim. (Cl. 88—16.4)

In the investigation of the anatomical and histological foundations of the three-color theory, the actions upon the retina which determine color-vision have been revealed and it was found that the three basic physiological sensations were evoked by specific stimuli, the physical value of which differs considerably from that hitherto assumed.

In practice, these investigations have led to fundamental rules which in all processes of direct or indirect, optical or mechanical color-reproduction, by the prism, lens or other screen method, on the basis of the three or two-color selection of the pictures, furnish the exact elements for the color analysis and for the color synthesis according to the addition principle.

At the present time, the analysis is obtained by the insertion of filters in front of the objective. These filters allow the production of monochromatic partial color components, that is to say the orange-colored, green and violet parts of the object are taken separately with almost complete neglect of the natural shading-effect of the object.

The process according to the invention replaces the said monochromatic partial color components by photographic partial pictures, which all show an almost complete shading of the object taken, and in which moreover: the green partial picture is isopanchromatic, that is to say it produces in black and white the physiological light-value, of all color-tones of the object; the orange-colored partial picture possesses in the positive as compared with the isopanchromatic partial picture a progressively decreased density in all the areas corresponding to the red, orange-colored and yellow parts of the object, but an approximately equal density in the areas corresponding to the greenish-yellow, and a progressively increased density in the areas corresponding to the green, blue and violet of the object; the violet partial picture possesses in the positive as compared with the isopanchromatic partial picture a progressively decreased density in the areas corresponding to the blue, red and violet parts of the object, and a progressively increased density in the areas corresponding to the orange-colored, yellow and green parts of the object.

Consequently, according to the invention, no actual color selection takes place, but the relative light and dark effect or shading of the individual partial picture is modulated according to the color and the physiological brightness of the different parts of the object taken.

These improvements lead to soft and harmonious color effects, which do not hurt the eye even in the special conditions of accommodation in semi-dark projection rooms. Moreover, the shading of the pictures remains perfectly true, that is to say the colors fade away in the shadows according to the strength of the light, without however altering their tone.

Fig. 1 illustrates diagrammatically the preparation of the negative of a two-color film.

Fig. 2 illustrates diagrammatically the preparation of the negative of a three-color film.

Fig. 3 illustrates diagrammatically the projection of the positive of a two-color film.

Fig. 4 illustrates diagrammatically the projection of the positive of a three-color film.

For the normal applications, for which the process according to the invention is intended, viz. scientific or documentary pictures of topographical and photogrammetrical nature, photographic surveying records, artistic and documentary films and so on, the separate photographic partial pictures must be produced with regard to the following practical rules:

25 (1) Using one and the same emulsion for all pictures, the ones to be selected from all the emulsions to be found in the trade being those which are sensitive to red up to the limits of the visible spectrum.

30 (2) Taking the isopanchromatic partial picture through a filter which corresponds to the one supplied by the manufacturer for the normalising of the emulsion employed (for example, the Agfa green filter 70 or 71 for natural or artificial light). The use of this filter is necessary because the panchromatic emulsions at present on sale show a sensitivity differing from the sensitivity of the eye, and therefore without a correcting filter they cannot produce isopanchromatic pictures.

35 (3) Using an orange-yellow or purple-colored filter for the taking of the second or third partial pictures. These filters must determine for the selected panchromatic emulsion a coefficient of the lengthening of the time of exposure which is equal to that of the normalising filter employed for the isopanchromatic partial picture.

40 This last rule, which is an empirical assumption, is nevertheless accurate, because it proportions the selective power of the filter to the time necessary for the exposure of a photographic material of a given sensitivity and with a given filter color.

45 The exact color of the orange-yellow or purple-colored filter must however harmonise with the

quality of the incoming light, that is to say either with natural light or with the various artificial light sources.

For the color synthesis, the three monochrome colored or filtered partial pictures, in greenish-blue, orange-yellow and purple-violet, must be added together on the projection screen by suitable optical, mechanical or physiological means.

The process is applicable with the observance of the same rules to photographic material with multicolor screens (autochromatic material) and to the various optical arrangements for prism or lens screen films.

In cases where for the obtaining of artistic or special sceno-graphical effects or in the film treatment elements of a personal chromatic interpretation are to be introduced with facility, then the operation is advantageously carried out according to the two-color system with the use of one isochromatic photographic picture and one picture taken through an orange-red filter. The reproduction of color is then not quite correct but the colors themselves can be modified at will by alteration of the filter at the projection stage. The inaccuracies are far less serious than those which arise in the processes at present employed so that the method according to the invention can certainly find application for most kinds of artistic films.

The alternate production of three-color pictures true to nature and artistic two-color pictures may often be desirable. In this case the procedure is carried out substantially according to the following scheme, given by way of example:

By means of suitable optical or mechanical devices, two pictures of reduced size are formed simultaneously or in rapid sequence upon the film section reaching an ordinary photograph, one of these pictures having always to be iso-panchromatic.

The second picture of reduced size must be of the described orange-red type—in case it is a question of the production of two color pictures—for the whole series of exposure.

If, on the other hand, it is a question of the production of three-color pictures, then each photograph must have its isopanchromatic picture associated alternately with an orange-yellow and a purple-colored picture. In the posi-

5 tive, each picture is dyed to the appropriate color.

The projection takes places with a normal apparatus in such a way that at the picture aperture there always appear two pictures of reduced size, the pictures being combined by means of a suitable optical device and brought to register exactly upon the screen.

10 In case the directly projected film section is a two-color film section, the synthesis of colors is obviously direct and immediate, but if, on the other hand, it is a question of a three-color film, there will be obtained two incomplete color 15 syntheses for every two photograph, which will however be combined chromatically by addition upon the retina.

20 Among the advantages of the process according to the invention there is especially to be named the fact that the color effect is obtained without raising the cost of cinematographic production.

25 What we claim is:

In a method of three-color photography of the kind in which on different portions of a single light sensitive surface are produced three differently selected component images, the step of 30 producing on the panchromatic emulsion, through a filter rectifying the specific sensitivity of the panchromatic emulsion used so as to reproduce in black and white the physiological light intensity of all the chromatical tones of the original, an isopanchromatich negative, and through an orange-yellow and through a purple filter two color selected negatives, the step of 35 producing positives of the said negatives and the step of projecting, in superimposition on a screen, pairs of positives comprising alternatively an isopanchromatich positive together with an orange-yellow component positive, and an iso-panchromatich positive together with a purple component positive, the said positives being projected through colored filters and precisely the isopanchromatich positive through a green filter, the orange-yellow component positive through an orange filter and the purple component image through a violet filter, the two 40 different pairs of optically superimposed component images being added on the retina in consequence of their rapid succession on the screen.
